CLAIM

The ornamental design for a beverage dispenser, as shown and described.

DESCRIPTION

FIG. 1 illustrates a front perspective view of the beverage dispenser;

FIG. 2 illustrates a front elevation view of the beverage dispenser of FIG. 1;

FIG. 3 illustrates a rear elevation view of the beverage dispenser of FIG. 1;

FIG. 4 illustrates a top view of the beverage dispenser of FIG. 1;

FIG. 5 illustrates a bottom view of the beverage dispenser of FIG. 1;

FIG. 6 illustrates a left side elevation view of the beverage dispenser of FIG. 1; and,

FIG. 7 illustrates a right side elevation view of the beverage dispenser of FIG. 1.

The broken lines in the drawings are included for the purpose of illustration and form no part of the claimed design.
